UNITED STATES PATENT OFFICE.

JAMES L. CRANDALL, OF MALDEN, MASSACHUSETTS.

BILGE BLOCK.

Application filed October 23, 1922. Serial No. 596,224.

To all whom it may concern:

Be it known that I, JAMES L. CRANDALL, a citizen of the United States, residing at Malden, in the county of Middlesex and 5 State of Massachusetts, have invented an Improvement in Bilge Blocks, of which the following is a specification.

This invention relates to bilge-blocks for dry docks, and has for its object to improve 10 the construction of the same to the end that a very substantial block may be produced, capable of resisting or supporting a heavy weight, which may be operated easily even when the weight is upon it.

15 The invention may consist of a base-block and a bilge-engaging block pivoted thereon and rollers which are adapted to roll upon each other and the base and bilge-engaging blocks whereby to raise and lower the bilge- 20 engaging block; and said rollers and blocks may be so arranged as to be set in the raised position of the bilge-engaging block whereby to maintain the bilge-engaging block in raised position; and the invention also consists in means to operate said rollers.

30 Fig. 1 is a side elevation of a bilge-block for dry-docks embodying the invention, the bilge-engaging block being lifted into its normal or raised position to engage the bilge of the vessel.

Fig. 2 is a view similar to Fig. 1 but illustrating the bilge-engaging block in lowered position.

Fig. 3 is a front view of the bilge block of 35 Fig. 1.

Fig. 4 is a section along line 4-4 of Fig. 1.

Fig. 5 is a sectional detail of the bilge-block raising and lowering mechanism taken 40 along line 5-5 of Fig. 3.

Fig. 6 is a front view of the lower roller of the mechanism.

As here shown the bilge-engaging block 10 is or may be mounted upon and pivoted 45 to the base-block 11 by the pivot-members 12, and said pivot members may be of any suitable construction as, for instance, that illustrated in my Patent No. 808,072, dated December 26, 1905. Said pivot members 50 may be formed or provided with inwardly-directed projections 12^a which are adapted to engage, whereby to limit the extent of the raising movement of the bilge-engaging block.

55 The means for raising and lowering the bilge-engaging block is located at the outer

end thereof opposite its pivotal connection and between said bilge-engaging block and said base block 11.

The raising and lowering means may include a plate 14 which is or may be secured to the under side of the bilge-engaging block. Said plate is or may be formed at its ends with the, preferably, cylindrically-formed cam faces 15, the axis of which is disposed transversely to said bilge-engaging block. The intermediate portion of the plate disposed between said cylindrically-formed faces 15 is formed or provided with gear teeth 16 which have a pitch line substantially coincident with said faces 15 and an axis substantially coincident with the axis of said cylindrically-formed faces.

A similar plate 17 is or may be secured to the upper face of the base-block and said plate may have its ends formed with the cylindrically-formed cam faces 18 and intermediate gear teeth 19 which have a pitch line substantially coincident with said faces 18 and an axis substantially coincident with the axis of said faces 18. Said cylindrical faces 18 may terminate in the horizontally-disposed flat faces 20 on which an operating roller is adapted to be supported in the raised position of the bilge-block, and said plate 17 is preferably formed with abutments 21 which are disposed at the ends of and extended above said flat faces 20 and are adapted to be engaged by an operating roller and restrict it from movement beyond its operated position.

The raising and lowering means may also include a lower roller 25 and an upper roller 26 adapted to engage and roll upon said plates 17 and 14 respectively. Said lower roller 25 is or may be formed with the cylindrical end-portions 27 adapted to engage and roll upon the cylindrically-formed faces 18 of said plate 17, and the intermediate gear-toothed portion 28 which is adapted to mesh with and rotate in contact with the gear teeth 19 of said plate 17. The pitch line of said gear toothed portion 28 is adapted to be substantially coincident with the faces of the cylindrical end-portions 27 of said roller 25. The upper roller 26 is or may be similarly formed and may have the cylindrical end-portions 30 which are adapted to engage and roll upon the cylindrically-formed faces 15 of said plate 14 and the cylindrical end-portion 27 of said roller 25, and the intermediate gear-toothed portion

31 which is adapted to mesh with the gear teeth 16 of said plate and also with the gear teeth 28 of said roller 25. The pitch line of the gear toothed portion 31 of said roller 26 is adapted to be substantially coincident with the faces of said end-portions 30.

5 Preferably said rollers 25 and 26 are of the same diameter.

Said rollers are or may be adapted to 10 maintain engagement and alignment with each other and with said plates 14 and 17 by the inter-meshing of the gear teeth of said rollers and plates although means preferably are provided to ensure the operative 15 engagement of said rollers and plates. For this purpose, said plate 14 may be formed or provided with the cylindrical pivot-members 35 disposed on opposite sides thereof and arranged concentrically with the axis of 20 the gear-toothed portion and cylindrically-formed faces thereof, and the upper roller 26 may be formed or provided with pivot-members which may comprise the reduced end-portions 36. Links 37 may be pivotally received on the pivot-members of said plate 25 and roller and secured in place by suitable means as cotter pins 38, whereby to connect the upper roller 26 to said plate 14 for rolling engagement therewith. The plate 17 30 may be similarly formed to provide the pivot-members 39 and the lower roller 25 may have the reduced end-portions 40 which comprise pivot-members. Links 41 may be pivotally received on the pivot members of 35 said plate 17 and roller 25 whereby to connect said roller to said plate for rolling engagement therewith. Said rollers 25 and 26 may be connected by links 42 which are pivotally received on the pivot-members of 40 said rollers. The arrangement of links is such that the rollers are held in operative engagement with each other and with said plates but the links are not herein designed to act to raise and lower the bilge-engaging 45 block, and the rollers and plates may function without said links.

Said lower roller 25 may be formed or provided with an extension 45 at one, or both, ends adapted to be engaged by a 50 wrench or other suitable tool by which to rotate said roller and actuate the mechanism to raise and lower the bilge-engaging block. A pawl 46 is or may be pivoted to the plate 55 17 and may be movable into engagement with the teeth of the lower roller 25 whereby to hold said roller, and consequently the bilge-engaging block, in raised position and lock the mechanism against operation; and said pawl must be removed from locking 60 position before the mechanism can be operated to lower the bilge-engaging block.

In the lowered position of the bilge-engaging block, the mechanism may be in some 65 position as illustrated in Fig. 2. When the bilge-engaging block is to be raised, the

lower roller 25 is rotated and consequently rolls upward upon the plate 17 of the base-block 11, due to the engagement of the gear teeth of said roller and plate. The rotary movement of said lower roller 25 also effects the rotation of the upper roller 26 in the reverse direction, due to the engagement of the gear teeth of said rollers, and said upper roller is consequently rolled upon the plate 14 of the bilge-engaging block 10 by 70 reason of the engagement of the gear teeth of said upper roller and plate. The inward movement of said rollers serves forcibly to raise the bilge-engaging block 10. In the extreme inward position, the rollers may assume a position slightly beyond the plane of the axes of the cylindrically-formed faces of the plates 14 and 17 with the lower roller supported upon the horizontally-disposed face of the plate 17 and in engagement with the abutments 21 of said plate, in which position said rollers may be held by the weight of the bilge-engaging block or the weight of the vessel supported by said block; and said pawl 46 may positively lock said rollers in 75 such position, whereby to lock said bilge-engaging block in raised position. When the pawl is removed from engagement with the lower roller, the bilge-engaging block may be lowered by rotating the lower roller in the proper direction whereby to move both rollers outwardly and permit the bilge-engaging block to descend.

I claim:

1. In a bilge-block, the combination of a 100 base-block, a bilge-engaging block pivoted thereto, and means for raising and lowering said bilge-engaging block including superimposed rollers disposed between said blocks and in rolling engagement with each other and said blocks, and means for driving said rollers.

2. In a bilge-block, the combination of a 105 pivotally connected base-block and a bilge-engaging block, both blocks provided with converging cam faces and means for raising and lowering the bilge-engaging block including superimposed rollers disposed between said blocks and the cam faces thereof and in rolling engagement with each other and said cam faces and means for driving said rollers upon each other and said cam faces.

3. In a bilge-block, the combination of a 110 base-block, a bilge-engaging block pivoted thereto, and both blocks provided with gear teeth, means for raising and lowering said bilge-engaging block including superimposed rollers disposed between said blocks and in rolling engagement with each other and said blocks, said rollers having gear teeth 115 adapted to mesh with the gear teeth of said blocks, and means for rotating said rollers.

4. In a bilge-block, the combination of a 120 pivotally connected base-block and a bilge- 125

engaging block, both blocks provided with converging cam faces, means for raising and lowering said bilge-engaging block including superimposed rollers disposed between 5 said blocks and the cam faces thereof and in rolling engagement with each other and said cam faces, said rollers having intermeshing gear teeth also disposed in mesh with the gear teeth of said blocks, and means 10 for rotating said rollers.

5. In a bilge-block, the combination of a pivotally connected base-block and bilge-engaging block plates having cam faces and gear teeth carried by the proximate faces 15 of said blocks, and means to raise and lower said bilge-engaging block including superimposed rollers disposed between and in rolling engagement with the cam faces of said plates and having engaging gear 20 teeth also arranged in engagement with the gear teeth of said plates, and means to rotate said rollers.

6. In a bilge-block, the combination of a base-block, a bilge-engaging block pivoted 25 thereto, and means for raising and lowering said bilge-engaging block including a roller disposed between said blocks in a position to roll upon said bilge-engaging block, and a second roller disposed between said blocks 30 in a position to roll upon said base-block and said first roller.

7. In a bilge-block, the combination of a base-block, a bilge-engaging block pivoted thereto provided with a lower cam face, and means for raising and lowering said bilge-engaging block including a roller disposed between said blocks in a position to roll upon said cam face and a second roller disposed between said blocks in a position to 40 roll upon said base block and said first roller.

8. In a bilge-block, the combination of a base-block, a bilge-engaging block pivoted thereto provided with gear teeth and means 45 for raising and lowering said bilge-engaging block including a roller disposed to roll upon said bilge-engaging block and having gear teeth arranged in mesh with the teeth of said bilge-engaging block and a second 50 roller disposed to roll upon said base block and said first roller and having a positive driving connection with said first roller.

9. In a bilge-block, the combination of a base-block, a bilge-engaging block pivoted 55 thereto provided with a lower cam face and gear teeth, and means for raising and lowering said bilge-engaging block including a roller disposed between said blocks in a position to roll upon said cam face and having gear teeth arranged in engagement with the gear teeth of said bilge-engaging block, and a second roller disposed between said 60 blocks in a position to roll upon said base block and said first roller.

65 10. In a bilge-block, the combination of a

base-block, a bilge-engaging block pivoted thereto, a plate carried by the lower face of said bilge-engaging block having a cam face and gear teeth, and means to raise and lower said bilge-engaging block including a roller 70 disposed between said blocks in a position to roll upon the cam face of said plate and having gear teeth engaging the gear teeth of said plate, and a second roller disposed between said blocks in a position to roll upon 75 said base block and said first roller.

11. In a bilge-block, the combination of a base-block provided with an upper cam face, a bilge-engaging block pivoted to said base-block and means for raising and lowering 80 said bilge-engaging block including a roller disposed between said blocks in a position to roll upon said bilge-engaging block, and a second roller disposed between said blocks in a position to roll in engagement with said 85 first roller and the cam face of said base-block.

12. In a bilge-block, the combination of a base-block provided with an upper cam face and gear teeth, a bilge-engaging block pivoted 90 to said base-block, and means for raising and lowering said bilge-engaging block including a roller disposed between said blocks in a position to roll upon said bilge-engaging block, and a second roller disposed between said blocks in a position to roll upon 95 said first roller and the cam face of said base-block and having gear teeth meshing with the gear teeth of said base-block.

13. In a bilge-block, the combination of a base-block, a plate having a cam face and gear teeth carried by the upper face of said base-block, a bilge-engaging block pivoted to said base-block, and means to raise and lower 100 said bilge-engaging block including a roller disposed between said blocks in a position to roll upon said bilge-engaging block, and a second roller disposed between said blocks in a position to roll in engagement 105 with said first roller and the cam face of said plate and having gear teeth meshing with the gear teeth of said plate.

14. In a bilge-block, the combination of a base-block provided with a cam face, a bilge-engaging block pivoted to said base block provided with a cam face and gear teeth, and means to raise and lower 115 said bilge-engaging block including a roller disposed between said blocks in a position to roll upon the cam face of said bilge-engaging block and having gear teeth meshing with the gear teeth of said block, and a second roller disposed between said blocks in a position to roll upon said first roller and the cam face 120 of said base block and having gear teeth meshing with the gear teeth of said first roller.

15. In a bilge-block, the combination of a base-block provided with a cam face and gear teeth, a bilge-engaging block provided 125

with a cam face and gear teeth and pivoted to said base-block, and means to raise and lower said bilge-engaging block including a roller disposed between said blocks in a position to roll upon the cam face of said bilge-engaging block and having gear teeth meshing with the gear teeth of said bilge-engaging block, and a second roller disposed between said blocks in a position to roll upon said first roller and the cam face of said base-block and having gear teeth meshing with the gear teeth of said first roller and the gear teeth of said base-block.

16. In a bilge-block, the combination of a base-block, a plate carried by the upper face of said base-block having a cam face and gear teeth, a bilge-engaging block pivoted to said base-block, a plate carried by the lower face of said bilge-engaging block having a cam face and gear teeth, and means to raise and lower said bilge-engaging block including a roller disposed between said blocks in a position to roll upon the cam face of the plate of said bilge-engaging block and having gear teeth meshing with the gear teeth of said plate, a second roller disposed between said blocks in a position to roll upon said first roller and the cam face of the plate of said base-block, and having gear teeth meshing with the gear teeth of said first roller and the gear teeth of the plate of said base-block.

17. In a bilge-block, the combination of a base-block, a bilge-engaging block pivoted thereto, and means to raise and lower said bilge-engaging block including co-acting superimposed rollers disposed between said blocks in a position to roll upon each other and said base and bilge-engaging blocks.

40. 18. In a bilge-block, the combination of a base-block, a bilge-engaging block pivoted thereto, said blocks provided with inclined faces directed toward each other, and means to raise and lower said bilge-engaging block including co-acting superimposed rollers disposed between said blocks in a position to roll upon each other and the inclined faces of said blocks.

19. In a bilge-block, the combination of a base-block, a bilge-engaging block pivoted thereto, said blocks provided with inclined faces directed toward each other, and means to raise and lower said bilge-engaging block including co-acting superimposed rollers disposed between said blocks in a position to roll upon each other and the inclined faces of said blocks, said rollers having gear-connection with said blocks.

20. In a bilge-block, the combination of a base-block, a bilge-engaging block pivoted thereto, said blocks provided with inclined faces directed toward each other, and means to raise and lower said bilge-engaging block including co-acting superimposed rollers disposed between said blocks in a position

to roll upon each other and the inclined faces of said blocks, said rollers having gear-connection with each other and with said blocks.

21. In a bilge-block, the combination of a base-block, a bilge-engaging block pivoted thereto, said blocks provided with inclined faces directed toward each other, and means to raise and lower said bilge-engaging block including co-acting superimposed rollers disposed between said blocks in a position to roll upon each other and the inclined faces of said blocks, and means to hold said rollers in a position corresponding to the raised position of said bilge-engaging block.

22. In a bilge-block, the combination of a base-block, a bilge-engaging block pivoted thereto, said blocks provided with inclined faces directed toward each other, and means to raise and lower said bilge-engaging block including co-acting superimposed rollers disposed between said blocks in a position to roll upon each other and the inclined faces of said blocks and means including a pawl arranged to engage one of said rollers and hold said rollers in a position corresponding to the raised position of said bilge and engaging block.

23. The combination of two pivotally-connected blocks provided with opposed cam-faces, and means to move said blocks about their pivotal connection including a pair of superimposed rollers disposed between and in rolling engagement with each other and said opposed cam-faces, said rollers and blocks provided with intermeshing gear teeth constructed and arranged to effect the positive rotation of said rollers upon each other and over said opposed cam-faces, and means to hold said rollers in the above-described relation with each other and said opposed cam-faces.

24. In a bilge-block, the combination of a base block, a bilge-engaging block pivoted thereto, said blocks provided with inclined faces directed toward each other, means to raise and lower said bilge-engaging block including co-acting superimposed rollers disposed between said blocks in a position to roll upon each other and the inclined faces of said blocks, and links pivotally connecting said rollers to each other and said blocks.

25. In a bilge-block, the combination of a base-block, a bilge-engaging block pivoted thereto, said blocks provided with inclined faces directed toward each other, and means for raising and lowering said bilge-engaging block including co-acting superimposed rollers disposed between said blocks in a position to roll upon each other and the inclined faces of said blocks, said rollers having reduced end-portions, and links pivotally received on said reduced end-portions and pivotally connected with said blocks.

26. In a bilge-block, the combination of a base-block, a bilge-engaging block pivoted thereto, said blocks provided with inclined faces directed toward each other, and means to raise and lower said bilge-engaging block including rollers disposed between said blocks in a position to roll upon each other
- and on the inclined faces of said blocks, and means to drive said rollers to roll upon each other and the inclined faces of said blocks. 10

In testimony whereof, I have signed my name to this specification.

JAMES L. CRANDALL.
